UNITED STATES PATENT OFFICE.

CHARLES J. DAVIDSON, OF MILWAUKEE, WISCONSIN.

FLOAT ALARM.

Application filed July 14, 1922. Serial No. 574,983.

To all whom it may concern:

Be it known that I, CHARLES J. DAVIDSON, a citizen of the United States, and resident of Milwaukee, in the county of Milwaukee and State of Wisconsin, have invented new and useful Improvements in Float Alarms, of which the following is a description, reference being had to the accompanying drawings, which are a part of this specification.

10 This invention relates to improvements in non-collapsible float alarms, more particularly adapted for indicating high or low water level in steam or other boilers.

15 Float alarms as now in general use are provided with floats of hollow construction which often lose their buoyancy due to leaks, with the result that the alarms do not properly function and the boiler is seriously injured, and there is the possibility of loss of 20 life if the boiler explodes.

25 It is one of the objects of the present invention to overcome the before mentioned objectionable features and provide a float alarm in which the float members are formed of solid metal, thus eliminating any question of 30 leaks or collapsing of the floats.

35 A further object of the invention is to provide a float alarm operated in part by solid counterweights which are submerged and 40 operated by the relative amount of water displaced to actuate the signal.

45 A further object of the invention is to provide a float alarm which may be easily attached to any boiler in a very simple manner.

50 A further object of the invention is to provide a float alarm which is of simple construction, is strong and durable, and is well adapted for the purpose desired.

55 With the above and other objects in view, the invention consists of the improved float valve and its parts and combinations as set forth in the claims, and all equivalents thereof.

45 In the accompanying drawing, in which the same reference characters indicate the same parts in all of the views:

Fig. 1 is a vertical sectional view of the improved float alarm; and

50 Fig. 2 is a transverse sectional view thereof taken on a larger scale on line 2—2 of Fig. 1.

55 Referring to the drawing, the numeral 5 indicates the casing which is in the form of two vertically extending tubular members 6 and 7 which are joined together in spaced

relation by an upper transverse tubular member 8 and a lower transverse tubular member 9, as clearly shown in the drawing. The tubular member 6 is formed with a lower opening 11 for connection with a boiler below water level line, and with an upper opening 10 for connection with the boiler above water level line or steam space. Both members also have openings 12 and 13 in their 60 lower ends for blow off connections, not shown.

The upper transverse member 8 is provided medially of its length with a fulcrum block 14 upon which are pivotally mounted 70 two float levers 15 and 16 having their outer end portions terminating adjacent the central portions of the tubular members 6 and 7. The high water float lever 15 is formed in two parts which are spaced apart and the 75 lever 16 is positioned therebetween and swings independently thereof. Medial portions of the levers are formed with upwardly and outwardly extending cam parts 17 and 18, the outer cam parts 17 being formed on 80 the lever parts 15 and extending to the right while the inner cam part 18 is formed on the low water lever 16 and extends to the left, as shown in the drawing. As thus constructed, the cam edges form a three point support for 85 a ball member 19 resting thereon, and which is moved upwardly when the right hand end of the lever 15 or the left hand end of the lever 16 is moved upwardly.

The ends of the lever 15 extending into 90 tubular casing member 6 are pivotally connected to the opposite sides of a tubular extension 20 of a high water solid metal float member 21 suspended therefrom. The opposite ends of said lever 15 which extend into 95 the tubular casing member 7 are pivotally connected to a tubular extension 22 of a solid metal counterweight float member 23 suspended from the lower end of said extension 22. The bores of the tubular extension 100 also extend downwardly through the respective float members.

The end of the lever 16 extending into the casing member 6 is pivotally connected to the upper end of a rod 24 which extends 105 loosely through the bore of the float member 21 and at its lower end is connected to a low water solid metal float member 25 suspended therefrom. The opposite end of said low water lever is connected to the upper end 110 of a rod 26 which extends through the bore of the extension 22 and the counterweight

float member 23, and at its lower end is connected to a counterweight float member 27.

The transverse member 8 is formed with an upwardly extending tubular portion 28 and the cap 28' has a spring controlled balanced valve 29 mounted therein which is provided with a downwardly extending stem 29'. The lower end of the stem rests upon the ball member 19 and the valve is moved to open position thereby. A steam or other pressure signal 30 is mounted in the upper end of the cap 28' and is adapted to be sounded when the water level in the boiler to which the alarm is connected rises above or drops below a predetermined level.

The counterfloats 23 and 27 are of such size and weight with relation to the float members 21 and 25 that when the floats 23, 25 and 27 are submerged and the float 21 is above the surface of the water, the floats 23 and 27 will counterbalance the floats 21 and 25, but if the water level drops below the upper portion of the float 25 the counterbalance will be changed to the extent of the less amount of water displaced, with the result that the float 25 will overbalance the float 27 and drop downwardly and move the valve 29 to open position and sound the alarm. On the other hand, if the level of the water rises to partly submerge the float 21, the amount of water displaced by said float will cause the float 23 to overbalance the float 21 and swing said float 21 upwardly and open the valve 29 to sound the signal. As the counterweight floats 23 and 27 are below the plane of the floats 21 and 25, they are submerged in a fluid at all times and their effective weight will be constant, but it is to be understood that the fluid in which the counterweights are submerged may be liquid or gaseous without departing from the spirit and scope of the invention.

From the foregoing description it will be seen that the float alarm is of very simple construction, and that as the float members thereof are formed of practically solid metal they cannot collapse or spring a leak and are therefore more durable and reliable.

What I claim as my invention is:

1. A float alarm, comprising a fluid chamber formed of two parts and having a normal liquid level, levers fulcrumed in said chamber, a substantially solid float connected to one of the levers and positioned in one of the chamber parts below the liquid level, a substantially solid float connected to the other lever and positioned above the liquid level in the same chamber, counterweight floats connected to the opposite ends of the respective levers and positioned below the

liquid level in the other chamber part, and an alarm means engaging medial portions of both levers and actuated by the movement of either lever when the liquid level rises above or drops below the said level. 65

2. A float alarm, comprising a float chamber having a normal liquid level, levers fulcrumed in said chamber and provided with cam portions, substantially solid floats connected to the levers at one end, one of said floats positioned below the water level and the other float positioned above the said level, substantially solid counterweight floats connected to the opposite ends of the respective levers and positioned below the liquid level, a valve actuated by said cam portions upon the movement of either lever when the liquid level rises above or drops below the said level, and an alarm means operated by the opening of the valve. 70 75 80

3. A float alarm, comprising a float chamber having a normal liquid level, levers fulcrumed in said chamber and provided with cam portions, substantially solid floats connected to the levers at one end, one of said floats positioned below the water level and the other float positioned above the said level, substantially solid counterweight floats connected to the opposite ends of the respective levers and positioned below the liquid level, a ball member resting upon the cam portions and moved by the movement of either lever, a valve actuated by the movement of either lever when the liquid level rises above or drops below the said level, and an alarm means operated by the opening of the valve. 90 95 100

4. A float alarm, comprising a pair of tubular members in communication with each other and having a normal liquid level, a pair of levers having cam portions and extending into the tubular members, ball members resting upon the cam portions, substantially solid metal floats connected to the respective levers at one end and extending into one of the tubular members, one of said floats extending below the liquid level and the other float positioned above said level, substantially solid metal counterweight floats positioned in the other tubular member below the liquid level and connected to the respective ends of the levers extending into the said tubular member, a valve having a stem which rests upon the ball member and actuated by the movement of either lever when the liquid level rises above or drops below the said level, and an alarm means operated by the opening of the valve. 110 115 120

In testimony whereof, I affix my signature.

CHARLES J. DAVIDSON.
